SPRINKLER

Clarence Lee Folden, Downers Grove, Ill., assignor to Sears, Roebuck & Co., Chicago, Ill., a corporation of
New York

Filed Dec. 6, 1963, Ser. No. 77,700

Term of patent 14 years

(Cl. D91—1)

The dominant features of my design are shown in solid lines.

I claim:

The ornamental design for a sprinkler, substantially as shown and described.
